(57) **CLAIM**

The ornamental design for a debris shield, as shown and described.

DESCRIPTION

FIG. 1 is a top perspective view of a debris shield showing our new design;

FIG. 2 is a bottom perspective view thereof, with the debris shield rotated 90 degrees;

FIG. 3 is a front elevational view thereof;

FIG. 4 is a left side elevational view thereof, the right side being a mirror image;

FIG. 5 is a rear elevational view thereof;

FIG. 6 is a top plan view thereof; and,

FIG. 7 is a bottom plan view thereof.

The broken lines shown in FIGS. 1–7 are for illustrative purposes only and indicate the nature and use of our new design; the form no part of our claimed design. The broken line circle immediately adjacent the shaded areas in FIG. 7 represent the bounds of the claimed design; the broken line circle and the area within the circle form no part of our design.
